United States Patent Office

Des. 212,261
Patented Sept. 17, 1968

212,261

PAIR OF SUN GLASSES

Maurice Bolle, 13 Rue Balland; and Robert Bolle, 58
Route de Marchon, both of Oyonnax, France; and
Richard Salvage, 1905 Avenue L., Brooklyn, N.Y.
11230

Filed Oct. 30, 1967, Ser. No. 9,217

Term of patent 14 years

(Cl. D57—1)

FIG. 1

FIG. 2

FIG. 4

FIG. 5

FIG. 3

FIG. 1 is a perspective view of a pair of sun glasses showing our new design;

FIG. 2 is a top plan view thereof;

FIG. 3 is a front elevational view thereof;

FIG. 4 is a side elevational view thereof; and

FIG. 5 is a rear elevational view thereof.

We claim:

The ornamental design for a pair of sun glasses, as shown.
